UNITED STATES PATENT OFFICE.

FRANK PEARSALL TAYLOR AND LOUIS HENRY HEPP, OF BROOKLYN, NEW YORK.

METHOD OF MAKING BOX-LINERS.

1,278,255.

Specification of Letters Patent. Patented Sept. 10, 1918.

Application filed September 6, 1917. Serial No. 189,994.

To all whom it may concern:

Be it known that we, FRANK PEARSALL TAYLOR and LOUIS HENRY HEPP, citizens of the United States, and residents of the 5 borough of Brooklyn, county of Kings, city and State of New York, have invented certain new and useful Improvements in the Method of Making Box-Liners, of which the following is a specification.

10 This invention relates to a device commonly termed a box liner. A device inserted inside of a common wooden box to protect the contents of the box from dampness or oxidation or other change in the contents 15 that might be occasioned by atmospheric action.

In the past it has been customary to make box liners of sheet tin, sheet lead, or other metallic substances, which substances are 20 formed as an internal box having soldered seams, and when the box is filled the overlapping portions of the liner are folded upon the contents and are soldered.

It is obvious that when liners are used for 25 certain materials such as gun cotton, explosives or even certain food products it is not practical to solder the closing portion or top as the presence of the necessary heat would be dangerous or unsatisfactory because of the change that the heat would produce in the contents of the box.

Another objection which our device is intended to overcome is the exceeding high cost of metallic box liners.

35 We have produced a box liner which fulfills all of the requirements and is economical of construction, and easy and satisfactory of operation. The device and its method of application will be described as the specification progresses.

40 The following is what we consider a good means of carrying out our invention and the accompanying drawings should be referred to for a complete understanding of the specification which follows.

In the drawings:—

Figure 1 shows a blank from which our box liner is produced.

45 Fig. 2 is a sectional view of a sheet from 50 which our liner is produced.

The remaining figures are on a small scale, and are intended as diagrams.

Fig. 3 shows the position of the liner in 55 end elevation when the first operation of formation is completed.

Fig. 4 shows the second operation completed.

Fig. 5 is an end elevation showing the completed liner with the top plate in position.

Fig. 6 is a plan view of a completed liner 60 in position in a filled box.

Similar reference numerals indicate like parts in all of the figures where they appear.

In producing our box liner we obtain a 65 plurality of sheets of suitable paper of any desired area. In the drawings the sheets are shown as oblong, and the box into which the liner is introduced is also oblong.

We take the two sheets of paper indicated at 1, and 2, and secure them together by means of a waterproof cement 3, and when this cement is thoroughly dried we apply to one side of one sheet of paper paraffin which has been heated to a liquid 75 state, and we give this exposed surface of one sheet a thorough and comparatively heavy coating of paraffin as indicated at 4 in Fig. 2.

When the paraffin is hard and dry we cut 80 from the sheets previously secured together and coated a blank of a desired size as shown in Fig. 1.

We next obtain a mold or shaping device 85 such as a block or box of desired area, an area just sufficient to fit loosely within the box for which our liner is to be formed, and placing the sheet, paraffin side downward, upon a table or other support, we arrange the mold or die centrally upon the 90 sheet so that it will occupy that space bounded by the lines 5, 6, 7 and 8 of the blank shown in Fig. 1. We then turn upward the four sides of the sheet upon the lines 5, 6, 7 and 8, and this will cause the 95 creases or folds in the free portion of the sheet as indicated by the lines 9, 10, 11, 12, 13, 14, 15 and 16.

The shape of the sheet inclosing the 100 mold will then have the appearance of the

diagram Fig. 3, the portions 17 and 18 being the projecting ends.

The next step is to fold the ends 17 and 18 inward, the end 18 being turned inward upon the end of the mold, and the portion 17 folding over that portion 18. Before this fold is made we apply a waterproof cement between the two portions of the projecting ends 17 and 18, and all similar 10 ends. That is, we cement the interior surface of the oblong areas bounded by the lines 9 and 10, 11 and 12, 13 and 14, and 15 and 16 and the adjacent outer edges. The inward movement of the ends will 15 produce the diagonal folds 19, 20, 21 and 22.

Under each of the inturned portions 17 and 18 we place a coating of waterproof cement such as we have previously used, 20 and we force the ends firmly inward upon the cement so that the joints will be tight, and the portions adjacent to each other will be completely cemented together.

We call particular attention to the fact 25 that the ends and the overlapping portions of each of the ends 17 and 18 extend upward above the top line 23, of the mold or form.

When the device is produced as described 30 it is ready to be inserted into the box which it is to line. We, therefore, withdraw the mold from the open top of the shaped liner, and in this condition the liners may be shipped to their destination for use.

35 When it is desired to use a liner produced according to our method the box is prepared, a liner introduced therein, and the material intended for the box is placed within the liner. When the box is properly filled we place a sheet of the same duplex paper from which the liner has been produced across the contents of the box, taking care that the paraffin surface is nonadjacent to the content of the box.

40 The ends of the liner are now turned inward as indicated by the dotted lines 24 and 25 in Fig. 6, and then the sides are folded and turned inward as indicated by the lines 26, 27, 28 and 29. A coating of cement is

45 placed under the inwardly folded ends 24 and 25, and the inwardly folded sides and when pressed firmly downward are caused to adhere to each other and to the body of the liner.

50 We now take a second sheet of paper of the area of the top of the box, and after having applied to the inturned ends and sides a thorough coating of the cement we place this top sheet 29 over the inturned ends and 55 sides, and press it firmly downward. This contemplates the formation and closing of our liner, and the top of the box may be attached in the ordinary manner.

The cement used in the production of our 60 liner must necessarily be of waterproof ce-

ment. We have successfully employed a cement such as that used for waterproofing concrete work. For although this cement must be used when hot we do not find an objection to its use in forming or producing 70 the liner. If there is an objection to its use in applying the top plate 29 or in completing the closing of the liner we may employ another waterproof cement that may be used cold. We believe, however, that the application of the internal sheet indicated by the dotted line 30 in Fig. 5, and the fact that a comparatively low heat may be employed with the cement used by us will make it practical to use that cement even for the 80 purpose of closing the open end of the container. 75

It is obvious that in forming the container we also produce the sheets 29 and 30. It is also obvious that we may form our box liner 85 from a material such as paper and fabric cemented together or from any other similar and cheap materials that can be made thoroughly waterproof.

Should it be desired to retain moisture 90 within the material contained within the box the liner will be made in a manner differing from that described only to the extent that the paraffin containing surface will be interior of the liner instead of exterior as described. 95

Modifications in the shape or in the application of our device may be made within the scope of the appended claims without departing from the principle or sacrificing 100 the advantages of the invention.

Having carefully and fully described our invention what we claim and desire to secure by Letters Patent is:—

1. The method of producing a box liner, 105 which consists of forming a liner from duplex and waterproof fibrous material cementing the joints, placing a sheet of duplex and waterproof material within said liner folding the free edges of said liner 110 upon said interior sheet, and placing a second sheet over said folded portion as herein specified and for the purpose set forth.

2. The method of producing a box liner, 115 which consists of producing a blank of duplex and waterproof paper upon a mold, turning the edges of said paper around said mold, cementing the folds produced, arranging a sheet of similar material exterior and interior to the free edges of said liner, 120 and cementing said free edges to said interior and exterior sheets for the purpose set forth.

3. The method of producing a box liner 125 which includes obtaining a sheet of paper of a desired size, cementing one side of said sheet, attaching thereto a sheet of paper of approximately equal area, applying to the exposed surface of one said sheet a paraffin coating, arranging a mold upon the 130

uncoated surface of one said sheet, folding both said sheets about said mold, cementing the joints produced by said folds, and later folding inward the ends and sides of said 5 sheets, cementing said inturned edges, and placing a sheet over said cemented surface as and for the purpose set forth.

Signed at New York city, county and

State of New York, this 15th day of Aug.
1917.
